UNITED STATES PATENT OFFICE.

FRANK A. SHOEMAKER, OF BUFFALO, NEW YORK, ASSIGNOR TO JAMES STURDY, OF BUFFALO, NEW YORK, AND JOHN STURDY, OF CRAFTON, PENNSYLVANIA.

STEAM-BOILER FURNACE.

938,022.

Specification of Letters Patent. Patented Oct. 26. 1909.

Application filed August 6, 1908. Serial No. 447,221.

To all whom it may concern:

Be it known that I, FRANK A. SHOEMAKER, a resident of Buffalo, in the county of Erie and State of New York, have invented a new and useful Improvement in Steam-Boiler Furnaces; and I do hereby declare the following to be a full, clear, and exact description thereof.

My invention relates to steam boiler furnaces, its object being to provide a suitable furnace for burning the fuel economically and causing the entire combustion thereof so as to practically eliminate the discharge of smoke.

In the improved furnace I provide a suitable boiler, a combustion chamber below the same and two racks of upright triangular water tubes below and extending longitudinally of the boiler and on each side of the combustion chamber with the circulating water connections between the racks and the boiler, and firing magazines outside of said racks the flat outer faces of the tubes forming the inner walls of the firing magazines, so that in the combustion of the fuel the flame and unconsumed gases will pass from the magazines between the tubes into the combustion chamber where complete combustion takes place, the same passing in regular course to heat the boiler, and the water in circulation in the tubular racks serving to protect the same from burning and also to absorb a large amount of heat and so increase the heating properties of the apparatus. The openings between the water tubes are narrow on the side of the firing magazine and flare or increase in cross section toward the combustion chamber. Both the tubes and openings are conveniently made triangular in cross section, but I do not limit myself to this construction; as any construction having abrupt narrow openings for the incoming gases from the firing magazine with passages rapidly increasing in cross section toward the combustion chamber is within the spirit of my invention.

In the accompanying drawing Figure 1 is a side view showing the boiler in full lines and the furnace on the line 1—1 Fig. 3; Fig. 2 is a cross section on the line 2—2 Fig. 1; Fig. 3 is a horizontal section on the line 3—3 Fig. 2; Fig. 4 shows in its upper

part a side view of one of the headers and connecting tubes, and in its lower part a sectional view thereof; and Fig. 5 is a cross section on the line 5—5 Fig. 4.

The invention may be applied to any suitable boiler, that shown being an ordinary fire tube boiler, as at 1, built within suitable brick work, the front wall of the brick work being shown at 2, the side wall at 3, the rear wall at 4. Underneath the front part of the boiler is the combustion chamber 5 and on each side thereof are the racks 6 formed of a series of upright tubes separating the combustion chamber from the firing magazines 7, the cross walls 8 forming the rear chambers of such firing magazines. The combustion chamber 9 through which the heated products of combustion pass in the rear of the boilers and up and back through the flues thereof, communicates with the chamber 10 leading to the chimney or flue.

The tubular racks 6 extend for the full length of the firing magazines and form their inner walls. They are preferably set at an upward and outward incline as shown, to properly confine the fuel in the magazines and provide increased space in the upper part of the central combustion chamber for the purpose hereinafter described. Such racks can be of any desired construction provided their main portions are formed of tubes having suitable water circulating connections with the boiler. We prefer to construct the same in the following way: The tubes are cast with suitable headers 11, 12, there being two tubes 13 connecting each header, and the racks being formed by bolting the tubes and headers together, as shown, the lower headers resting on suitable longitudinal walls 14, being held in place by depending lips 15, while the upper headers have like upwardly extending lips 16 adapted to contact with the boiler body 9 and bearing against suitable flanges 17 riveted to the boiler. To give circulation through these tubes I provide the down-take pipe 18 having suitable pipe connections 19 with the lower headers 11, and also provide 100 pipe connections 20 leading from the upper headers 12 into the boiler as shown. As shown in the drawings the tubes 13 have suitable webs or fins 21 extending from the

upper headers down a suitable distance to confine the fuel within the firing chamber 7, such webs being preferably cast with the tubes.

5 The firing or fuel chambers 7 have suitable grates 22 at the bottom thereof and are provided with fuel doors 23 at the top and with ash pit doors 24 and clinker doors 25 in the front wall, the positions of the several doors 10 being illustrated in Fig. 2. The pipe racks 6 form the inner walls of such combustion chambers, and I prefer to form such racks of triangular tubes as shown, having their longitudinal flat faces 26 outward so as to 15 form the inner walls of the firing chambers, such flat faces serving to confine the fuel in the chambers and preventing the dropping of the fuel through the rack into the combustion chamber, while the spaces 27 20 between the other two sides 28, 29, of the triangular tubes form flaring openings for the escape of the flame and gases from the firing chambers, as hereafter described. It is preferred that the tubes shall form right 25 angled triangles in cross section with their faces 28 at right angles to the outer faces 26 toward the rear of the furnace and their inclined faces 29 toward the front of the furnace so that such flaring openings 27 shall 30 extend backwardly and direct the flame and gases toward the rear of the boiler.

In the operation of the furnace the fuel is fed to the firing chambers through the fuel doors 23, a suitable depth of fuel being 35 maintained in such chambers and the same extending well to the top of the same, the fuel being confined by the racks and the escape of the flame and gases from the upper part of the firing chamber 7 into the combustion chamber 5 being prevented by the webs 21 between the upper parts of the tube. A suitable supply of air is admitted to the combustion chamber 7 by openings both at the top and bottom of the fuel bed, such as 40 by opening the top or fuel doors 23 and the ash pit doors 24, the only points of admission for air being at the top and bottom of said firing chambers, so that all the air to support combustion is caused to pass through 45 said firing chambers and is superheated therein, part of it causing combustion in the firing chambers while the remainder passes with the flame and unconsumed gases into the central combustion chamber, such superheated air being brought into intimate contact with the gases by passing through the slits or openings between the upright tubes and immediately uniting with any unconsumed gases, giving the complete combustion 55 of the same, and the flame from the two firing chambers is drawn by the draft generated by the chimney flue through the chamber 9 under and around the boiler, returning through the boiler flues and then 60

passing through the flue 10, an intense white 65 heat being maintained within the combustion chamber and all of the gases from the coal being perfectly consumed so that no smoke is formed and escapes from the furnace. In such operation the flaring spaces 70 27 between the two flues provide for immediate expansion of the gases after passing through the slits between the tubes and on account of such flaring spaces extending backwardly the flame can flow directly back 75 without obstruction through the combustion chamber into the chamber 9, the peculiar shape of the tubes providing for such expansion of the gases and their combustion with the influent air, this being one reason 80 why such complete combustion and high heat is generated. In this way the furnace is a great economizer of fuel, providing for the preliminary generation of the gases, the intimate contact of the air with the fuel to 85 cause complete gasification of the same, the superheating of the air within such mass of fuel, and the complete combustion either in the firing chambers or directly upon entering the combustion chamber, as above described.

The fresh fuel fed to the firing chambers is heated and gasified on account of the high combustion therein and the gases so formed are drawn downwardly to points below the webs, passing down through the fire bed and being in this way so heated that even when fresh fuel is fed to the firing chambers no unconsumed gases escape from the furnace. The fuel thus settles down 95 gradually within the firing chambers and becomes incandescent and only the ash and clinker reaches the bottom of that bed, when the same can be withdrawn through the ash pit or clinker doors.

When it is desired to cut down the heat of the furnace air is admitted through the door 30 into the central chamber, while the inlet doors to the firing chambers are closed. This results in the immediate checking of the heat and the fires in the magazines are in this way banked and can be maintained in that condition for many hours without waste of fuel. By closing such central door and opening the doors to the firing magazines the 100 fires are found to come up very quickly and a perfectly clear flame free from smoke immediately be obtained. The heat generated in the firing chambers and within the combustion chamber around the pipe rack and the down-take pipe leading to the same is absorbed by the water in circulation through such racks, a large volume of heat being thus absorbed, causing a rapid circulation of 105 water through the pipe racks, leading both to the superheating of the water of the boiler and to the generation of steam within the racks themselves, so largely increasing the 110

water heating powers of the furnace. At the same time the racks and their connecting pipes are properly cooled so that all liability of burning out the same is overcome, a durable furnace construction being thus provided. By forming the tubes of the racks integral with the headers the number of joints required is reduced to a minimum and the liability of burning out the parts or of 10 leakage is prevented.

Practical use of the invention has demonstrated that a perfect combustion is obtained and that even when fresh fuel is fed to the firing chambers all the gases are consumed 15 and the furnace produces practically no smoke. The furnace is a great economizer of fuel, requiring only about two-thirds of the fuel required in an ordinary boiler furnace to produce the same heat units. Full 20 access is given to the firing chambers to provide for the removal of clinker, ash, etc., and to the central chamber for repairs, and but little labor is required in the operation of the furnace.

25 What I claim is:

1. A boiler furnace having a boiler, a combustion chamber, a rack of water tubes connected to the boiler, and a firing magazine separated by the rack from the combustion 30 chamber, the passages through the rack between the water tubes being flaring and wider at the outlet end facing the combustion chamber than at the inlet end.

2. A boiler furnace having a boiler, a combustion chamber, a firing magazine and a 35 rack of water tubes substantially triangular in cross section separating the combustion chamber from the firing magazine, the spaces between the said tubes forming the 40 only passage for gases from said firing magazine to said combustion chamber and being of increasing width from their inlet ends toward their outlets into the combustion chamber.

45 3. A boiler furnace having a boiler, a combustion chamber below the boiler and two firing magazines, two racks of water tubes separating said combustion chamber from said firing magazines, the passages between 50 the tubes flaring toward the combustion chamber and presenting abrupt narrow openings for the incoming gases from the firing magazines.

4. A boiler furnace having a fire tube 55 boiler, a combustion chamber beneath it, two racks of substantially triangular water tubes below and connected to said boiler and enclosing said combustion chamber and having a passage between them leading to said fire tube boiler, and a firing magazine outside of 60 said racks, the triangular water tubes presenting flat faces to the firing magazine.

5. A boiler furnace having a combustion chamber below the boiler, two racks of up-

right water tubes below and extending longitudinally of the boiler, and firing magazines outside of said racks, the firing magazines having two air openings respectively, adjacent to their upper and lower portions, and the water tubes having substantially flat 70 outer faces and passages between them flaring toward the combustion chamber.

6. A boiler furnace having a combustion chamber below the boiler, two racks of upright water tubes below and extending longitudinally of the boiler, and fuel magazines outside of said racks, the tubes of the racks having flat outer faces forming the inner walls of the firing magazine and abrupt narrow openings between said faces. 80

7. A boiler furnace having a combustion chamber below the boiler, two racks of water tubes below and extending longitudinally of the boiler, firing magazines outside of said racks, the tubes of the racks being triangular 85 in shape and having their outer faces forming the inner walls of the firing magazines.

8. A boiler furnace having a combustion chamber below the boiler, two racks of water tubes below and extending longitudinally of the boiler, firing magazines outside of said racks, the tubes of said racks being right angled triangles in cross section and having their outer faces forming the inner walls of 90 the firing magazines. 95

9. A boiler furnace having a combustion chamber below the boiler, two racks of upright water tubes below and extending longitudinally of the boiler, firing magazines outside of said racks, the firing magazines 100 having feeding doors in their upper portions and ash pit doors at the base thereof, and the tubes having webs on their upper portions closing the spaces between them.

10. A boiler furnace having a combustion chamber below the boiler, two racks of upright water tubes below and extending longitudinally of the boiler, fuel magazines outside of said racks, the tubes of the racks being triangular in shape and having webs 105 on their upper portions closing the spaces between them, and the firing magazines having feeding doors above said webs.

11. A boiler furnace having a combustion chamber below the boiler, two racks of upright water tubes below and extending longitudinally of the boiler, firing magazines outside of said racks, said tubes being triangular in cross section, their flat faces forming the inner walls of the firing magazines 115 120 and the flaring spaces in the combustion chamber between said tubes extending backwardly on the line of draft.

12. A boiler furnace having a combustion chamber and a firing magazine and a single 125 rack of water tubes separating them, the openings between the tubes being abrupt and flaring toward the combustion chamber.

13. A boiler furnace, having a boiler, a combustion chamber, a separate firing magazine having two air-openings at its top and bottom portions respectively, a rack of water tubes separating said firing magazine from said combustion chamber, said tubes having openings between them increasing in width toward the combustion chamber, and a pas-

sage from said combustion chamber to said boiler.

In testimony whereof, I the said **FRANK A. SHOEMAKER** have hereunto set my hand.

FRANK A. SHOEMAKER.
